(57) **CLAIM**

The ornamental design for a launching apparatus for spinning toy top, as shown.

DESCRIPTION

FIG. 1 is a bottom view of the launching apparatus for spinning toy top showing our design;

FIG. 2 is a front view thereof;

FIG. 3 is a left side view thereof;

FIG. 4 is perspective view thereof;

FIG. 5 is a rear view thereof;

FIG. 6 is a right side view thereof; and,

FIG. 7 is a top view thereof.

1 Claim, 7 Drawing Sheets
